[57] CLAIM

The ornamental design for a hand-held viewer for navigational charts or the like, as shown and described.

DESCRIPTION

FIG. 1 is a isometric view of a hand-held viewer for navigational charts or the like showing my new design; FIG. 2 is a top plan view thereof; FIG. 3 is a side elevational thereof; the opposite side being a mirror image of the side shown; FIG. 4 is a bottom plan view thereof; FIG. 5 is an end elevational as seen from the left of FIG. 1; and, FIG. 6 is an end elevation as seen from the right of FIG. 1.

*Fig. 4.**Fig. 5.**Fig. 6.*
